UNITED STATES PATENT OFFICE.

DAVIS J. HINSON, OF LAKE CHARLES, LOUISIANA.

LIQUID-FUEL BURNER.

1,128,447.

Specification of Letters Patent. Patented Feb. 16, 1915.

Application filed June 9, 1914. Serial No. 844,029.

To all whom it may concern:

Be it known that I, DAVIS J. HINSON, a citizen of the United States, residing at Lake Charles, in the parish of Calcasieu and State of Louisiana, have invented certain new and useful Improvements in Liquid-Fuel Burners; and I do hereby declare the following to be a full, clear, and exact description of the invention, such as will enable others skilled in the art to which it appertains to make and use the same.

This invention comprehends certain new and useful improvements in liquid fuel burners and has for its primary object to provide a device of this character which will be of simple construction and operation as well as highly efficient in use and especially adapted for cook stoves and the like.

Another object of this invention is to provide a liquid fuel burner having an improved form of volatilizer and burner proper.

Another object of the invention is to provide a burner of this character which will be cheap of construction as well as strong and durable and highly efficient in use.

This invention has for a further object to generally improve and simplify the construction and operation of devices of this character and increase the efficiency thereof without materially increasing the cost of the same.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which—

Figure 1 is a top plan view of my improved burner, partly in section, Fig. 2 is a side elevation with parts in section, Fig. 3 is an end elevation, and Fig. 4 is an enlarged detail perspective view of one of the supporting blocks.

Referring in detail to the drawings by numerals, 1 designates the liquid feed pipe leading from a suitable supply tank, not shown, and having a valve 2 for controlling the flow of liquid through said pipe 1.

A suitable elbow 3 is positioned upon the free extremity of the feed pipe 1 and has an

extension pipe 4 secured therein and positioned at right angles to said pipe 1, a T connection 5 or the like being secured upon the free end of said pipe 4 and having the oppositely directed discharge pipes 6 secured therein and extending at right angles to said pipe 4, the free extremities of said pipes 6 being open, the purpose of which will presently appear.

Engaged against the elbow 3 is one end of a helical spring 7 which has its opposite end bearing against a cap 8 engaged in the rear end of the sleeve 9, which has its forward end secured in the large T 10 having the pipes 11 projecting therefrom in opposite directions and at right angles to the sleeve 9, said T 10 inclosing the small T 5, while the pipes 11 inclose the pipes 6. It will also be understood that the large T 10 and pipes 11 form the volatilizing chamber of the device and as the liquid escapes from the free ends of the pipes 6, it drips into the pipes 11 of said volatilizing chamber to be converted into a gas, as the pipes 11 are positioned directly over the burner caps 12, which are perforated and rest upon the burner plates 13.

The small T 5 is retained in proper position by means of the supporting and spacing perforated disk 14 engaged around the forward end of the pipe 4 and positioned in the forward end of the sleeve 9, and it will be readily understood that as this disk 14 is perforated, the gas generated in the volatilizing chamber will also enter the sleeve 9, and should the gas be generated faster than it is consumed, the cap 8 will be forced out of the rear end of the sleeve 9 against the tension of the spring 7 to permit escape of the excessive amount of gas, when the spring 7 will return the cap 8 to normal position.

The gas generated in the volatilizing chamber escapes from the same by way of the pipes 15 connected at their upper ends with the elbows 11' mounted upon the free extremities of the pipes 11 and having the reducers 16, secured therein, said pipes 15 being considerably smaller than the pipes 11 and threaded in the reducers 16. The opposite ends of the pipes 15 are connected, as shown at 17, with the burner nozzles 18, then through the burner plates 13, said burner plates 13 resting upon the connections 17 and being provided with air inlet openings 19, as will be readily understood by referring to the drawings.

It will be understood that the nozzles 18,

burner plates 18 and burner caps 12 constitute the burners proper. The burners proper are suitably spaced below the pipes 11 and above the drip pan 20, which has the 5 supporting blocks 21 removably positioned in its opposite ends having inclined sides 21' while the transverse supporting channels 22 are formed in the upper central portions of said blocks 21, within which are engaged 10 the horizontally extending portions of the pipes 15, whereby the complete device may be properly supported above said pan 20, within which the oil may be permitted to drip from the burner nozzle 18 to be ignited 15 when starting operation of the device. It will also be readily understood that suitable valves 23 are positioned in the curved portions of the pipes 15, whereby the flow of oil or gas through the same may be readily 20 controlled, and it will be apparent that during operation of the device, the blaze will spread from the perforations of the burner cap 12 to the pipes 11 of the volatilizing chamber to heat the same and thereby 25 create gas to be fed to the burner nozzles 18 and consumed at this point.

From the foregoing it will be readily apparent that I have provided a liquid fuel burner which will be simple in construction 30 and operation and it will be understood that any number of arms 11 may be included in the volatilizing chamber with a burner proper positioned beneath the same. It will further be understood that many minor 35 changes in the details of construction and arrangement of parts may be made within the scope of the appended claims without departing from the spirit of the invention, or sacrificing any of the advantages thereof.

Copies of this patent may be obtained for five cents each, by addressing the "Commissioner of Patents, Washington, D. C."

What is claimed is:—

1. A device of the class described comprising a liquid conducting pipe, a volatilizing chamber, an extension pipe secured to said liquid conducting pipe and extending into the volatilizing chamber, a sleeve projecting from said volatilizing chamber, a cap positioned in said sleeve, means engaged around said extension and bearing against said cap to resiliently retain the latter in the end of said sleeve, burners beneath said volatilizing chamber, means for conducting gas from said volatilizing chamber to said burners, means for controlling the flow of gas to said burners, a drip pan, and means positioned in said drip pan for supporting 50 said burners above the same.

2. A device of the class described comprising the combination with a drip pan and volatilizing chamber; of burners between said drip pan and said volatilizing chamber and including nozzles, burner plates positioned upon said nozzles and having air openings, perforated burner caps positioned upon said burner plates, connections between said burners and said volatilizing chamber, means for controlling the flow of gas from said chamber to said burners, means for feeding a liquid to said volatilizing chamber, and removable supports 65 positioned in said drip pan for supporting 70 the burners and the volatilizing chamber.

In testimony whereof I affix my signature in presence of two witnesses.

DAVIS J. HINSON.
